DELAYED-ACTION SWITCH

Joseph B. Shockley, Detroit, Mich.

Application July 28, 1952, Serial No. 301,280

5 Claims. (Cl. 200—34)

1

In my prior U. S. Patent No. 2,572,396, granted to me October 23, 1951, I describe a delayed action switch wherein the actual breaking of a circuit therethrough may be variably controlled to occur at a timed interval after the switch button or tumbler has been moved to its "off" position; so that when the switch is used in connection with a porch light, for instance, a person after snapping off the switch may have time to descend the porch steps before the light is actually extinguished. This type of switch has many advantages in many other applications where such timed delay is desirable.

While the switch of my earlier patent referred to is of somewhat special design, as a whole, the present invention relates to the use of a conventional switch design with a delayed action latching device added thereto and coupled to a moving member thereof in a simple and effective manner. This permits the utilizing of a standard switch mechanism without departing from its customary mechanical and operating features and admits of the coupling thereto of an accessory comprising a time control latch without necessarily calling for any material redesign or modification of the switch mechanism itself.

The invention more particularly contemplates in combination with a standard switch having a toggle operated blade adapted to be snapped into circuit-closing and circuit-breaking positions upon the actuation of a tumbler or button for that purpose, an attachment in the form of a latch plate movable with said blade, and a timed latch to engage said latch plate when said blade is moved to its circuit-closing position, thereby causing said latch plate to temporarily prevent the movement of said blade to a circuit-breaking position for a period of time after the tumbler or button has been actuated to bias said blade toward its circuit-breaking position.

Still further, the said invention contemplates providing, in combination with a standard toggle switch having a circuit-controlling blade, a guided slideable latch plate connected to the free end of said blade, a latch button adapted to be pressed into latching engagement with said plate when said blade is in a circuit-closing position, and means for moving said button out of engagement with said plate after a predetermined timed interval.

Still further objects or advantages additional or subsidiary to the aforesaid objects, or resulting from the construction or operation of the invention as it may be carried into effect, will become apparent as the said invention is herein-after further disclosed.

In carrying the said invention into effect, I may adopt the novel construction and arrangements of parts hereinafter described, by way of example, having reference to the accompanying drawing, wherein:

2

Figure 1 is a front elevation of a switch and its mounting strap showing the arrangement of the switch button and the delay regulating button;

5 Figure 2 is a vertical section of the same taken on a plane indicated by the line 2—2 in Figure 1;

Figure 3 is a detail elevation of the reciprocal latch plate removed;

10 Figure 4 is a rear view, taken on a plane indicated by the line 4—4 in Figure 2, wherein the back cover plate of the switch casing is removed;

Figure 5 is a similar view to Figure 2 illustrating, in full lines, the switch button moved to the "on" position, the latch plate being engaged by the delay action latch and, in broken lines, the switch button moved to the "off" position while the contact blade remains held by the latch plate in its "on" position;

15 Figure 6 is a fragmentary sectional plan view taken on a plane indicated by the line 6—6 in Figure 5; and

20 Figure 7 is a similar view to Figures 2 and 5 showing the switch button in its "on" position and the contact blade also in its "on" position notwithstanding the fact that the upward movement of the latch plate is interfered with to some extent by premature depression of the latch button.

25 Similar characters of reference indicate similar parts in the several figures of the drawing.

30 Figure 10 indicates a switch casing provided with a mounting strap 11 and having mounted therein a switch button or tumbler 12 pivoted at 13 and connected with one end of a toggle spring 14, the other end of which is connected to a vertically swingable contact blade 15; all in a well-known manner whereby, upon the depression of the tumbler 12 to the "off" position shown in Figure 2 the said blade 15 is snapped downwardly to its circuit-breaking position shown in that figure, whereas, when the said tumbler is raised to the "on" position shown in full lines in Figure 5, the said blade is snapped upwardly to the circuit-closing position bridging the contacts 16 as in standard toggle switch practice.

35 Added to this conventional mechanism, I provide a latch plate 17 having a slot 18 in its lower portion and a square orifice 19 at its upper end portion, the said slot 18 being adapted to receive

40 a tongue or a projection 15' on the free end of the contact blade 15. The said plate is reciprocable in guide channels 20 formed in a back plate 21 secured to the casing 10 of the switch. Thus,

45 as the contact blade 15 is snapped upwardly or downwardly the said latch plate 17 correspondingly reciprocates upwardly or downwardly in its guide channels.

50 Above the switch mechanism, the casing 10 is shown as being bored at 22 to receive an expandable piston 23 which may be pushed inwardly of

the said bore against the resistance of a compression spring 24 by means of a push button 25.

This expandable piston 23 is mounted on a rod 27 the rear end portion of which is of square section and the forward end rounded and threaded to receive the said push button 25. The piston 23 is compressible between the inner end of the said button 25 and a washer or shoulder 26 intermediate of the length of the said rod 27. The rear end of the said rod 27 slides in a square hole 28 through the switch casing at the inner end of the said bore 22.

When the latch plate 17 is raised upon the contact blade being snapped to its circuit-closing position, the orifice 19 in the upper end of this blade normally coincides with the hole 28 in the casing 18, so that, by pushing the button 25 inwardly, the inner end of the rod 27 may then enter the orifice 19 of the latch plate 17 and thereby secure the said latch plate in its raised position until such time as the rod 27 is withdrawn therefrom by the action of the compression spring 24.

In the example shown, the time required for the compression spring to release the rod 27 from the latch plate is controlled by the frictional resistance between the piston 23 and the wall of the bore 22; and this resistance may be regulated by rotary adjustment of the button 25 on the threaded end of the rod 27 to determine the amount of expansion of the said piston against the wall of the bore. This particular method of control is not an essential feature of the present invention and was utilized with the construction described in my earlier Patent No. 2,572,396 hereinbefore referred to.

It will be apparent that, in the organization described, when the tumbler is moved to the "on" position shown in full lines in Figure 5, and the latch plate 17 moved upwardly as the contact blade 15 bridges the contacts 16, the pressing of the button 25 inwardly as shown in the said Figure 5 will effect the temporary locking of the latch plate in this raised position. Consequently, if the tumbler be then moved to the "off" position, shown in broken lines in the said figure, it will not immediately cause the corresponding movement of the contact blade 15, even though its spring 16 will then urge such movement. It is only after the latch plate 17 is released by the delay movement of the piston 23 back to its outer position in the manner already described that the spring 16 may then complete the circuit-breaking movement of the blade 15.

It will be obvious that when the button 25 is not pressed inwardly the switch may be operated to its "on" and "off" positions in the normal manner; and even if the said button 25 be prematurely pressed inwardly so that the inner end of the rod 27 is impinged by the upper edge of the latch plate 17, as shown in Figure 7, the switch may still be operated in the normal manner to its "on" and "off" positions and the closing and opening of the circuit effectively accomplished.

It will also be observed that, as this invention does not reside in the specific form of timing means for controlling the operation of the latch rod 27, the said invention is of a quite simple nature involving the combination with a time-controlled latch member and a standard toggle switch mechanism including a movable contact blade of a latch plate adapted to be coupled to said blade and guided for movement thereby into and out of latching juxtaposition with said latch member. Thus it will be seen that a standard toggle switch may, by simple modification of its

casing to house a slideable latch plate and its latch (which is entirely independent of the switch mechanism), be converted to a delayed-action switch such as in the manner illustrated, as an example, in the drawing forming part of this specification.

This invention may be developed within the scope of the following claims without departing from the essential features of the said invention, and it is desired that the specification and drawing be read as being merely illustrative of a practical embodiment of the same and not in strictly limiting sense.

What I claim is:

1. In combination with a standard switch mechanism including a contact blade movable to "on" and "off" positions, a slidably mounted reciprocable latch plate having a permanent sliding connection with said blade, a manually operable latch member normally separated from said latch plate adapted to engage and detain said plate in one of its positions of movement, and time-controlled means for effecting delayed disengagement of said latch member from said plate.
2. In combination with a standard toggle switch mechanism including a contact blade swingable to "on" and "off" positions, a slidably mounted reciprocable latch plate having a permanent sliding connection with the free end of said blade, a manually operable latch member normally separated from said latch plate adapted to engage and detain said plate in one of its positions of movement, and time-controlled means for effecting delayed disengagement of said latch member from said plate.
3. In combination with a standard switch mechanism including a contact blade movable to "on" and "off" positions, a slidably mounted reciprocable latch plate having a permanent sliding connection with said blade, a push button, resilient means opposing the pushing of said button, a latch member normally spaced from said latch plate adapted to interlockingly engage and detain said plate in one of its positions of movement when said button is pushed inwardly against said resilient means, and braking means for delaying the outward plate-disengaging movement of said button by said resilient means.
4. In combination with a standard switch mechanism including a contact blade movable to "on" and "off" positions, a slidably mounted reciprocable latch plate having a permanent sliding connection with said blade, a push button, resilient means opposing the pushing of said button, a latch member normally spaced from said latch plate adapted to interlockingly engage and detain said plate in one of its positions of movement when said button is pushed inwardly against said resilient means, and adjustable braking means for variably delaying the outward plate-disengaging movement of said button by said resilient means.
5. Switch mechanism as in claim 1, wherein the latch member includes a push button operated rod and the engagement between the latch plate and latch member includes an opening in the latch plate for the reception of said rod.

JOSEPH B. SHOCKLEY.
